CLAIM

The ornamental design for a display screen or portion thereof with animated graphical user interface, as shown and described.

DESCRIPTION

FIG. 1 is a front view of a first image of a display screen or portion thereof with animated graphical user interface; and, FIG. 2 is a front view of a second image thereof.

The appearance of the figures sequentially transitions between FIGS. 1-2. The process or period in which one image transitions to another forms no part of the claimed design.

The outermost broken lines illustrate portions of the display screen and form no part of the claimed design. The remaining broken lines illustrate portions of the graphical user interface and form no part of the claimed design.
